CASING FOR A PORTABLE ELECTRONIC CALCULATOR

Edward T. Liljenwall, Sunnyvale, Calif., assignor to
Hewlett-Packard Company, Palo Alto, Calif.

Filed Feb. 1, 1971, Ser. No. 111,799

Term of patent 14 years

Int. Cl. D14—02

U.S. Cl. D26—5 C

Figure 1

Figure 2

Figure 3

FIG. 1 is a rear perspective view of a casing for a portable electronic calculator showing my new design;

FIG. 2 is a front perspective view of the casing of FIG. 1; and

FIG. 3 is a bottom perspective view of the casing of FIGS. 1 and 2.

I claim:

The ornamental design for a casing for a portable electronic calculator, as shown.
